GAS COMPRESSOR

Carl A. Bergmann, Milwaukee, Wis., assignor to
Walter D. Mann, Milwaukee, Wis.

Application October 25, 1935, Serial No. 46,807

19 Claims. (Cl. 230—108)

The present invention relates in general to improvements in gas compressors, and relates more specifically to improved apparatus for compressing air or other elastic fluids with the aid of centrifugal force acting upon a carrier liquid.

Generally defined, an object of the invention is to provide improved apparatus for producing high compression of gases in a substantially isothermal manner and with maximum efficiency.

10 While it has heretofore been proposed to utilize an ordinary centrifugal pump for the purpose of hydraulically compressing air to some extent, by mixing the air with the liquid passing through the pump rotor and by subsequently separating the air from the mixture expelled by the rotor, this method of compression is relatively inefficient and is not adapted for high compression of the gas.

In applicant's prior Patent No. 2,025,037, a compressor is shown and described, which is designed to effect any desired degree of compression of a gas with a minimum expenditure of power by utilizing centrifugal force to compress the fluid while mixed with liquid, and by additionally utilizing the pressure acting upon the separated liquid to regain the energy which is substantially wasted when utilizing the ordinary centrifugal pump for air compression purposes. The compressor shown in said prior patent is further designed to produce substantially isothermal compression of a gas to relatively high pressures in a single stage; to minimize friction losses and leakage; and to produce entirely automatic and continuous operation wherein the fluent compressing medium is repeatedly utilized and retained at a desired temperature.

The present invention is designed to retain all of the above-mentioned advantageous features and to provide certain improvements as follows:

40 To provide a compressor having a rotor wherein in the cross sectional area of the ducts is smaller toward the outer rim to thereby maintain or increase the velocity and overcome the tendency of the air bubbles to "slip", that is, to travel backward.

To provide a device of the class described wherein the rotor ducts are so shaped as to prevent premature separation of the air from the water.

50 To provide a compressor wherein diffusion of the air and water takes place at the outer rim of the rotor.

To provide a compressor wherein the rotor ducts are pointed against the direction of rotation of the rotor at the discharge end of said

ducts to thereby regulate the absolute discharge speed of the compressing fluid, as desired.

To provide a compressor wherein the rotor ducts are substantially oval in shape to keep the hydraulic losses to a minimum.

To provide a compressor of the class described wherein the gas is mixed with the liquid in such a location and manner as to provide for efficient operation.

To provide a compressor which is self-priming, 10 which has novel means for effecting a seal between movable and stationary parts, and which has a bearing member and frictional sealing member which are automatically lubricated by the cooling liquid.

15 With the above and other objects in view, the invention consists of the improved gas compressor and all its parts and combinations as set forth in the claims, and all equivalents thereof.

In the accompanying drawings in which the 20 same reference numerals designate the same parts in all of the views,

Fig. 1 is a transverse vertical sectional view of the compressor;

Fig. 2 is a fragmentary front end view of the 25 rotor, parts being broken away and shown in section;

Fig. 3 is a similar view of the other end of the rotor, part of the stationary hub portion being shown in section;

Fig. 4 is a fragmentary sectional circumferential view of the rotor developed and taken on line 4—4 of Fig. 1;

Fig. 5 is a longitudinal sectional view through the stationary compressor part;

Fig. 6 is a diagram of forces illustrating the section of a particle passing through a duct to show the action of a particle of liquid passing through the compressor duct;

Fig. 7 is a velocity diagram of the mixture entering the rotor intake ducts;

Fig. 8 is a velocity diagram of the returning liquid entering the ducts of the stationary compressor part;

Fig. 9 is a vertical sectional view through a 45 modified form of compressor;

Fig. 10 is a fragmentary bottom view of the rotor of the modified form of compressor;

Fig. 11 is a circumferential section taken on line 11—11 of Fig. 10 and developed;

Fig. 12 is an enlarged fragmentary sectional view showing the float valve; and

Figs. 13—15 are side elevational views of a float in different positions to show the plane of operation.

Referring more particularly to the drawings, the numeral 12 designates a housing which may be suitably supported on legs 13. A shaft 14 is rotatably mounted in the housing and has one end journalled in a bearing 15. The shaft may be driven by any suitable means. Within the housing the shaft is formed with an annular flange 16 to which a rotor 17 is secured by bolts or the like 18.

10 The majority of the inner portion of the rotor terminates short of the shaft 14 as at 19 and 20, and a stationary compressor part or duct forming member 21, which is complementary in shape to said inner portion of the rotor fills 15 the space between the inner portions of the rotor and the shaft 14. The said stationary compressor part is provided with a tubular extension, the outer end of which is secured in an end opening of a cup shaped member 22, the said 20 member 22 being in turn fitted into a tubular boss 23 on the casing 12. An annular cover 24 has its outer periphery secured to the rotor 17 and has its inner periphery rotatably surrounding the tubular extension of the stationary compressor 25 part 21. A carbon ring 25 secured to one end of a bellows 26 is urged into sealing relationship with the inner portion of the annular rotatable cover 24 by a coil spring 27.

A bearing housing 28 is fitted into the member 30 22 and is formed with an upwardly extending tubular member 29 forming an air inlet duct 30 which communicates with an annular chamber 31. The bearing housing 28 supports a bearing 32 within which the other end of the shaft 14 is 35 journalled. A sealing ring 33 carried by one end of a bellows 34 is urged by a coil spring 35 into sealing relationship with the end of the shaft 14. The other end of the bellows is secured to a cap 36. It may readily be seen that air or other gas 40 under pressure which is delivered by the compressor to the duct 37 of the shaft 14 can pass through the bellows 35, past a non-return check valve 38 in the cap 36, and into a pipe 39 leading to a reservoir 40.

45 A water cooler 41 is adapted to receive water through an inlet valve 42, until a discharge valve 43 overflows. The water from the cooler is adapted to pass through a pipe 44 into duct 45 of the stationary compressor part 21 and into ducts 46 of said stationary compressor part.

The water cooler 41 is also provided with a suitable float controlled needle valve 42' to discharge air which might collect in the upper part of the cooler.

50 The ducts 46 of the stationary part of the compressor are curved as shown in Fig. 1 to register with passage ways 47 and 48 in the rotor and to cooperate therewith in forming a plurality of radially extending ducts which are substantially oval in cross section as shown in Fig. 1. The passage ways 47 form compression conduits and the passage ways 48 form liquid return conduits. When viewed from an end of the rotor, as in Fig. 2, the portion of the duct 47 which leads 55 to the duct 46 is curved as at 49, and the curve is formed by relatively small radii, and the adjoining portion of the duct 47 is of outwardly decreasing cross sectional area as shown in Figs. 1 and 2 and is formed by large radii to form an arc 60 approaching a straight line, and said arc is angled away from the direction of rotation of the rotor as at 47 (Fig. 2). The outer portion of the duct 47 then curves abruptly to the periphery of the rotor, also preferably in a direction opposed to the 65 direction of rotation of the rotor, as at 51, and

flares outwardly into communication with the peripheral separating chamber 52, and said portions 51 also angle inwardly toward the separating chamber to reduce eddy currents as shown in Fig. 4.

5 Guide vanes 46', formed in the stationary compressor part 21, direct water admitted to the duct 46 with the absolute speed and direction C₁ (see Fig. 7) past air intake slots 56 to the rotor entrance to give the water passing into the duct portions 49 the desired relative speed W₁. It can be noted that the direction of the absolute speed C₁ is pointed in the direction of the peripheral speed of the rotor U₁ in order to reduce the absolute speed and losses of the water going through the duct portions 47.

In Fig. 6 (a) represents the eye of a rotor and (b) represents a curved duct. M represents a particle such as a particle of liquid in the present invention passing through said duct with a relative speed W₁ (Fig. 7) while the duct rotates in the direction indicated by the arrow in Fig. 6.

20 Due to the peripheral speed U and radius (r) a centrifugal force (C) acts on the particle M in the radial direction indicated by the arrow at (C) to create one component C' acting perpendicular to the wall and another component C'' acting tangentially to the walls. Due to the radius R and the relative speed W an additional centrifugal force D acting in the direction of 25 radius R is set up, and in addition there is an accelerating force E due to the angular speed of the duct and the relative speed W of the particle, which is set up acting in a direction opposite to C'. In accordance with the above, the shape of 30 intake duct portions 49 and 47 of the rotor are so designed that the forces C', D and E cancel each other, and only the force C'' remains. This causes the particles to move through the ducts without being thrown against the walls and premature separation of the air or gas from the liquid is thus prevented. This makes efficient 35 operation possible.

40 Due to the rotation of the rotor, water admitted to the duct 46 of the stationary compressor part is projected by centrifugal force through the duct portions 49, 47 and 51. Air, which is sucked through an air cleaner 53, passes a non-return check valve 54, through duct 30, into the chamber 31, and through passage way 55 to air intake slots 56. Water passing into duct portions 47 produces a Venturi effect and entrains air from the slots 56 which communicate with air passage ways 56', and the mixture of air and water passes through the compression duct portions 47, the air being in the form of small bubbles in the water and the columns of water being subjected to progressively increasing centrifugal force. Inasmuch as straight rotor ducts or ducts having ordinary or involute curves would tend to 45 permit undesirable separation of the air bubbles from the water, resulting in an inefficient compressor, the ducts in the present invention have been carefully planned as above described by reference to the diagram of Fig. 6 to prevent such 50 premature separation.

55 Due to the curvature and flare of the ducts at 51 (see Fig. 2) the circulating speed of the mixture is reduced, which in turn causes higher pressure at the outer rim of the rotor and also 60 assures complete separation of the air from the water at the proper time.

65 When the peripheral separating conduit 52 is reached, the air or gas under high pressure is 70 expelled from the liquid by the continued action 75

of centrifugal forces thereon to the inner portion 58 of the conduit 52, whereupon the float valves 59, which are pivoted as at 60, will ride in partially submerged condition upon the liquid level 61 to 5 admit the compressed air to the ducts 62, the latter leading to the conduit 37 in the shaft 14 and ultimately to the reservoir 40 as above explained.

The float 59 is shown in detail in Fig. 12, and 10 it may be seen that this float comprises a piece of relatively light material or metal 63 and a short length of heavier material or metal 64 secured to one end thereof. The entire float is fulcrumed as at 60 near one end of the light section of metal. 15 The amount of both materials and the point of fulcruming are so worked out that the float balances on the fulcrum when it is approximately half submerged in the liquid which is used.

Figs. 13, 14, and 15 explain the principle of 20 this special float. Fig. 13 shows the float half submerged in liquid, and it will be noticed that the float is balanced. Fig. 14 shows the float fully submerged in liquid, and it will be noted that due to the difference in specific gravity, the 25 length of the lighter material 63 displaces more water than the length of the heavier material 64 so that the end 63 is lifted up by the liquid. Thus, with the float as applied to applicant's apparatus, this movement would cause a closing 30 movement of the valve to prevent escape of water. In Fig. 15 the action of this type of float, when entirely unsubmerged, is shown. Due to the greater weight and leverage of the lighter section 63, there would be a downward tilting of this 35 end.

From the above it may be seen that the lighter portion 63 may be half or partially counterbalanced by a heavier section 63, and the materials can thus be either lighter or heavier than 40 the liquid employed. Ordinary floats must, of course, be lighter. With this float construction therefore, solid metal can be used which is necessary in the present use due to the tremendous pressures to which the material of the float is 45 subjected. Ordinary floats sufficiently small in size would fail to stand up under the pressure conditions. A spring 65 urges the valve to closing position when the compressor is idle to prevent liquid from entering the air discharge ducts.

The water in the peripheral conduit 52, from 50 which the air has been separated, flows in the return duct portions 48 due to the lesser head of liquid in these duct portions which is sufficient to overcome the friction of the liquid flowing 55 through the rotor. The pressure and peripheral speed of the particles of the liquid are reduced while they return through conduits 48. The kinetic energy due to the peripheral speed of the liquid which is imparted to the particles of the 60 liquid passing through the conduits 47 where they gradually reach the maximum peripheral speed in the conduits 52 is returned in conduits 48. The slower relative speed in the peripheral duct 52 is maintained through the ducts 48 to keep 65 the hydraulic losses as low as possible. The water is ultimately discharged into the ducts 46 for repetition of the cycle.

Referring to Fig. 8, the relative speed W_2 is 70 pointed away from the direction of the peripheral speed U_2 as at 66 (Fig. 3) to obtain the desired absolute speed C_2 , so that the water enters the ducts at 63' with no pressure and with said speed C_2 , which absolute speed is slightly higher than 75 the absolute speed C_1 to overcome the friction of

the water passing through the ducts 46 and cause continued repetition of the cycle.

The operation of this form of compressor is as follows: To start the compressor it is rotated in the direction indicated by arrows, and water is 5 admitted to the cooler 41 through the intake valve 42 until the discharge valve 43 overflows, which valve is set at the same pressure as the static pressure in the duct 46 of the stationary compressor part. The water then flows through a 10 pipe 44, duct 45 of the stationary compressor part 21 into the ducts 46 and begins to circulate. The movement of the water in the ducts entrains air from the vane slots 56 as above explained in detail, and the separated compressed air is 15 directed into the reservoir 40 as before explained, the water alone returning to the duct portions 46.

An annular space 67 within the rotor will be filled with water to the annular level 68. As soon as maximum air pressure is reached in the 20 reservoir 40, a piston controlled valve 69 is moved to the right, referring to Fig. 1, against the tension of a spring 70 to bring a port 71 in the stem of the piston into registration with a duct 72 in the valve casing and thereby admit air 25 from a pipe line 73 to a pipe line 74, and the pipe line 74 leads to the space in a cylinder 75 above a piston 76, which piston is mounted rigidly on a control tube 77. When the air enters the cylinder 75, it will force the piston down- 30 wardly to move the control tube against the tension of the coil spring from the full line position of Fig. 1 to the dotted line position therein. This causes the open inner end of the control tube to be positioned in the duct 46. Water circulating 35 rapidly through the duct 46 of the stationary rotor part will pass into the open end of the control tube, through said tube and into the annular space 67 of the rotor, and said water fills the annular space to the approximate water 40 level 78.

As soon as enough air has been taken from the compressed air reservoir 40 to bring the pressure therein to a predetermined minimum, the spring 70 will move the control valve 69 back to 45 the full line position of Fig. 1 to thereby cause the port 71 in the piston stem to register with the duct 79 in the valve casing, and thus connect the pipe line 74 with the atmosphere. This naturally relieves the pressure on top of the control 50 tube piston 76 and permits the tube to return to the full line position of Fig. 1. When in this position, the water in the annular space 67 of the rotor will enter the opening 80 in the upper end of the control tube and will be forced rapidly 55 back into the ducts 46 and into the circuit for the compressor. The compressor will therefore again begin to compress air. When the compressor is idle, the water will drop to the lower portion of the compressor to the indicated level 81. This 60 method of control is particularly adaptable for portable units which are driven by gas engines or the like, where the periods of rest are brief. For stationary work where electric motors are used and where the periods of rest are prolonged 65 a suitable electric control may be employed.

During operation, part of the circulating water in the system continually passes out of opening 82 through duct 83 into pipe line 84 to the water cooler 41. Due to the fact that the intake opening 82 for the cooling water is pointed against the direction of the circulating water, the kinetic energy of the water is transferred partially into pressure to eliminate the necessity of using a 70 pump for driving the water through the cooler. 75

This water is cooled and returned through the tube 44 and canal 45 into the circuit of the water. Openings 85 in the compressor casing admit air from the exterior, which air is blown out 5 through other casing openings 86 to produce an additional cooling effect. The bearing 32 and the sealing ring 33 are of oilless construction being lubricated by the cooling water. The cooling water which is admitted at 88 cools the liquid 10 passing through the cooler 41. The reservoir 40 is also provided with a safety pressure relief valve 81.

The heat generated during the compression of the gas, is quickly absorbed by the carrier liquid 15 thereby maintaining the compression substantially isothermal. Due to the absorption of the heat of compression of the liquid, this liquid upon entering the passages 46 will be heated, and in order to maintain the carrier liquid at substantially uniform temperature, a portion thereof is 20 permitted to pass through the cooler 41.

The annular separating conduit 52 communicates with an annular compressed gas collecting duct 58 and the duct 52 insures a perfect balancing of the rotor. In case one compression conduit discharges more liquid than the other conduits, the annular level of the liquid is quickly equalized by the centrifugal force and the balance of the rotor is not destroyed.

30 The water which is condensed during operation of the compressor raises the static pressure within the stationary compressor part ducts and is discharged through discharge valve 48.

In Figs. 9 to 11, there is illustrated a modified 35 form of compressor which differs from the compressor heretofore described principally in the mode of regaining the energy of the carrier liquid after the compressed gas has been liberated.

Referring first to Fig. 9, it will be seen that there 40 is a suitable base 90 which supports a lower stationary compressor part 91. The center lower portion of said stationary compressor part supports a bearing 92 through which a vertical shaft 93 is journaled, said shaft having an axial duct 45 94 therein which communicates with its lower end. The upper end of the shaft is journaled in a bearing 95 which is suitably supported by an upper casing part 96, said upper casing part being supported on flanges 97 of the stationary compressor 50 part. The shaft 93 may be suitably driven by a prime mover 98 of desired form.

Within the casing 96 and rigidly mounted on an upper portion of the shaft 93 for rotation therewith, is a rotor 99. It is to be noted that 55 the rotor in this form of the invention cooperates with the stationary compressor part 91 to form ducts which are substantially oval in shape as shown in Fig. 9, said ducts being otherwise very similar in construction to the compressor ducts 60 in the form of the invention shown in Fig. 1.

Referring to Fig. 10, it may be seen that the ducts are also designed to prevent premature separation of the gas from the liquid as heretofore described in detail in connection with the principal form of the invention.

To start the compressor, it is rotated through 70 operation of the motor 98, and water is forced through an intake valve 100 of a water controlling device 101. The water flows through a pipe 102 into the ducts 103 of the stationary compressor part, and circulates through the system until a discharge valve 104 overflows, said valve being set at the same pressure as the static pressure at the point 105 in the compressor when the compressor 75 is in operation.

The water circulates through the stationary ducts 103 of the compressor and through ducts 106 in the rotor. Guide vanes 111 formed on an end of the stationary compressor duct 103, are formed in a similar manner to the guide vanes 5 46' shown in Fig. 6. Water circulating through the ducts 103 in the direction indicated by the arrows in Fig. 9 passes these guide vanes, and a Venturi action takes place to entrain air from slots in the guide vanes which slots are similar 10 to the slots 56' shown in Fig. 6. The mixture of air and water then passes through the duct portions 106 of the rotor in the manner heretofore described in detail in connection with the form of the invention shown in Fig. 1, and the mixture 15 ultimately reaches the annular separating chamber 112 where the compressed air is liberated from the liquid and collects in the annular air space 113. Float valves 114, which are similar in action to the valves heretofore described in connection with Fig. 1, control the passage of compressed air from the chamber 113 through ducts 115 into the conduit 94 in the shaft 93. The air then passes a non-return check valve 116 into a pipe 117 leading to a compressed air reservoir 25 similar to the reservoir 40 of the principal form of the invention.

The water which is separated from the air is forced through water discharge nozzles 118 with the relative speed W, (see Fig. 11) which speed 30 is nearly as great as the peripheral speed U of the nozzles 118, and the speed W is approximately opposed to the direction of the peripheral speed U, as shown in Fig. 11. The water enters the ducts 103 of the stationary compressor part at 35 119 with the relative speed C and reenters the rotor ducts 106 with the slightly less speed due to the hydraulic losses in passing through the ducts 103.

The reaction of the jets of liquid delivered at 40 high velocity from the nozzles 118 during rotation of the rotor serves to simultaneously diffuse the pressure on the carrier liquid so as to augment the compression of the compressed gas and to assist in driving the rotor, thereby reducing the energy 45 losses to a minimum. In this machine, as in the one previously described, the compression is effected by centrifugal force acting upon liquid columns within the ducts 106 and the separation of the liquid and gas is likewise effected by centrifugal force within the rotor.

Air or gas is admitted through an air cleaner 120, tube 121, into space 122, within the casing. From said space, the air enters through non-return check valves 123 into the annular air 55 space 124 which in turn communicates with the slots in the vanes 111 where the air is introduced into the water circuit as heretofore described.

A part of the nozzles 118 are supplied with float controlled needles 125 which are of well known construction and which are adapted to vary the cross sectional area of the nozzles and serve to prevent the air from blowing through the nozzles by maintaining the annular water level in the annular ducts 113 at a level closer to the 60 center of the rotor than the nozzle openings.

Cooling water may enter a pipe 126 in the water controlling device 101. When the compressor is operating, pressure is built up within a space 127 within the sealing bellows 128 at 70 the lower end of the shaft 93. Said pressure is transmitted through a tube 129 to a chamber 130 in the water controlling device 101. The said pressure in the chamber 130 acts on a bellows 131 to open a valve 132 and admit the cool- 75

ing water to the system through the pipe 102. This water forms part of the circulating water in the system and maintains the carrier liquid at a substantially uniform temperature. The 5 water is ultimately discharged through the valve 104.

When the compressor is idle, the air pressure within the spaces 127 and 130 disappears and the valve 132 is closed so that no cooling water 10 is consumed. When the compressor is idle, the water in the compressor flows to the lower portion of the stationary compressor part and into the annular space 133 to approximately the level 134. When the compressor is started, the water 15 within the annular space 133 flows through small openings 135 into annular space 136 and is raised by the centrifugal action within said space to the rotor ducts 106. The annular ledge 137 within the rotor space 133 prevents the water from getting to the outer portion of the rotor where it would cause too much friction.

During operation, additional water which is fed into the compressor, causes the average pressure of the circulating water to rise and when said 25 pressure reaches a predetermined point, water is discharged through the discharge valve 104, which as before mentioned, opens at the same pressure as the desired static pressure at 105.

By referring to Fig. 10 it will be seen that the 30 duct shapes shown in this figure are identical with the shapes of the ducts in the first described form of compressor, except that the cross section of the ducts is not enlarged at the outer portion of the rotor. However, in this form of the invention the water substantially maintains the speed on its way throughout the rotor until it passes the annular separating chamber 112, and it increases its velocity, due to the shape of the nozzles, to the speed W (see Fig. 11) when leaving 35 the rotor, and little energy is left in the water 40 which reenters the stationary ducts 103.

From the foregoing description it will be apparent that the invention provides a compact 45 and efficient gas compressor wherein the actual compression and separation of the gases under pressure is effected with the aid of centrifugal force within a single rotor. The deceleration or diffusion of the carrier liquid is utilized in various ways to augment the gas compression, and the 50 compressed gas is always delivered from the machine in relatively dry condition. It will also be seen that the compression is substantially isothermal. The heat resulting from the compression 55 may be utilized for heating or other purposes thereby reducing the energy losses to a minimum.

It is apparent that the invention is adapted 60 for many uses wherever the compression of gas is employed, such as in connection with refrigeration and gas turbines.

It should be understood that it is not desired 65 to limit the invention to the exact details of construction and operation herein shown and described, for various modifications within the scope of the claims may occur to persons skilled in the art.

What I claim is:—

1. In a compressor, a rotor having therein a plurality of compression conduits extending away from the rotor axis, means for delivering mixed 70 gas and liquid into the inner portions of each of said conduits, means communicating with said compression conduits for separating the compressed gas from the liquid, and means for independently conducting gas and liquid away from 75 said separating means, said compression conduits

having their inner portions curved away from the direction of rotation of the rotor and then extending with less curve approaching a straight line toward the periphery of the rotor to prevent premature separation of the gas from the liquid. 5

2. In a compressor, a rotor having therein a plurality of compression conduits extending away from the rotor axis, means for delivering mixed 10 gas and liquid into the inner portions of each of said conduits, means communicating with said compression conduits for separating the compressed gas from the liquid, and means for independently conducting gas and liquid away from 15 said separating means, said compression conduits having their inner portions curved away from the direction of rotation of the rotor and then extending with less curve toward the periphery of the rotor and having their outer portions flared into communication with the separating means.

3. In a compressor, a rotor having therein a 20 plurality of compression conduits extending away from the rotor axis, means for delivering mixed 25 gas and liquid into the inner portions of each of said conduits, means communicating with said compression conduits for separating the compressed gas from the liquid, and means for independently conducting gas and liquid away 30 from said separating means, said compression conduits having their outer portions flared into communication with the separating means. 30

4. In a compressor, a rotor having therein a plurality of compression conduits extending away from the rotor axis, means for delivering mixed 35 gas and liquid into the inner portions of each of said conduits, means communicating with said compression conduits for separating the compressed gas from the liquid, and means for independently conducting gas and liquid away 40 from said separating means, said compression conduits having their outer portions flared and 45 angled inwardly into communication with the separating means.

5. In a compressor, a central shaft, a fixed 45 compressor part loosely surrounding said shaft and having a plurality of conduits therein, a rotor 50 rotatable with the shaft around said fixed compressor part and having compression conduits 55 communicating with one end of the conduits of the fixed compressor part and return conduits 60 communicating with the other end of the conduits of the fixed compressor part, the ends of the conduits of the fixed compressor part which adjoin the compression conduits being separated by a plurality of vanes having axial slots, means 65 for admitting gas to the slots of said vanes, and 70 means for admitting liquid to the conduits of the fixed compressor part, said liquid being movable upon rotation of the rotor past said vanes and into the compression conduits to entrain gas 75 from the slots in said vanes. 60

6. In a compressor, a central shaft, a fixed 65 compressor part loosely surrounding said shaft and having a plurality of conduits therein, a rotor rotatable with the shaft around said fixed compressor part and having compression 70 conduits communicating with one end of the conduits of the fixed compressor part and return conduits communicating with the other end of the conduits of the fixed compressor part, the ends of the conduits of the fixed compressor part which adjoin the compression conduits being separated by slotted vanes, means for admitting 75 gas to the slots of said vanes, and means for admitting liquid to the conduits of the fixed compressor part, said liquid being movable upon ro- 75

- tation of the rotor past said vanes and into the compression conduits to entrain gas from the slots in said vanes, said vanes being pointed toward the direction of rotation of the rotor.
5. 7. In a compressor having a rotor and having a plurality of compression conduits therein extending away from the rotor axis, means for delivering mixed gas and liquid into portions of said conduits, means for separating the compressed 5 gas from the liquid, a reservoir to which said compressed gas is conducted, means for returning the separated liquid back to said compression conduits, and means responsive to a predetermined pressure in said reservoir for temporarily 10 removing liquid from the circuit of said rotor conduits to render the compressor temporarily inactive.
8. In a compressor having a rotor and having a plurality of compression conduits therein extending away from the rotor axis, means for delivering mixed gas and liquid into portions of said conduits, means for separating the compressed gas from the liquid, a reservoir to which said compressed gas is conducted, means for returning 15 the separated liquid back to said compression conduits, and means responsive to a predetermined pressure in said reservoir for temporarily removing liquid from the circuit of said rotor conduits to render the compressor temporarily inactive, there being an annular chamber 20 within the rotor for receiving said removed liquid.
9. In a compressor having a rotor and having a plurality of compression conduits therein extending away from the rotor axis, means for delivering mixed gas and liquid into portions of said conduits, means for separating the compressed gas from the liquid, a reservoir to which said compressed gas is conducted, means for returning 25 the separated liquid back to said compression conduits, and means responsive to a predetermined pressure in said reservoir for temporarily removing liquid from the circuit of said rotor conduits to render the compressor temporarily inactive, said means being responsive to a drop 30 in pressure in said reservoir for returning the removed liquid to the rotor conduit circuit.
10. In a compressor having a rotor and having a plurality of compression conduits therein extending away from the rotor axis, means for delivering mixed gas and liquid into portions of said conduits, means for separating the compressed gas from the liquid, a reservoir to which said compressed gas is conducted, means for returning 35 the separated liquid back to said compression conduits, and a by-passing tube in the interior of the rotor movable in response to a predetermined pressure in said reservoir to a position 40 in the rotor conduits to intercept liquid therefrom and temporarily remove the same from the circuit.
11. In a compressor having a rotor and having a plurality of compression conduits therein extending away from the rotor axis, means for delivering mixed gas and liquid into portions of said conduits, means for separating the compressed gas from the liquid, a reservoir to which said compressed gas is conducted, means for returning 45 the separated liquid back to said compression conduits, and a by-passing tube in the interior of the rotor movable in response to a predetermined pressure in said reservoir to a position 50 in the rotor conduits to intercept liquid therefrom and temporarily remove the same from the circuit, said tube being movable in response to a drop in pressure in said reservoir to return the removed liquid to the rotor conduit circuit.
12. In a compressor having a rotor, a shaft for said rotor having a duct therein, compression conduits in said rotor, means for delivering mixed gas and liquid to said compression conduits, means for separating compressed gas from the liquid, means for conducting said separated gas to the duct in the rotor shaft, and means for conducting the compressed gas away from said duct in the rotor shaft including a bellows, a sealing ring on an end of the bellows, and yielding means for urging the ring into frictional engagement with a portion of the rotor shaft 55 around the duct opening.
13. In a compressor having a rotor within which fluid is circulated, a fixed member about which said rotor revolves, and means for preventing loss of fluid from said rotor comprising a bellows surrounding said fixed member and having one end fixed and closed, a sealing ring on the other end of said bellows, and yielding means for urging said sealing ring into frictional engagement with the rotor.
14. In a compressor having a rotor provided with ducts therein through which a compressing liquid is circulated by centrifugal force, a cooling unit, connections between said cooling unit and the rotor ducts, and means for utilizing the kinetic energy of the liquid to circulate said liquid through the cooling unit.
15. In a compressor, a rotor having therein a plurality of compression conduits extending away from the rotor axis, means for delivering mixed gas and liquid into the inner portions of each of said conduits, means communicating with said compression conduits for separating the compressed gas from the liquid, means for conducting gas away from said separating means, return conduits for conducting the liquid from the separating means back to the compression conduit, nozzles for discharging the separated liquid from the separating means into the return conduits, and float controlled valves for regulating the liquid level adjacent the nozzles to prevent gas from escaping from said nozzles.
16. In a compressor, a rotor having therein a plurality of compression conduits extending away from the rotor axis, means for delivering mixed gas and liquid into the inner portions of each of said conduits, means communicating with said compression conduits for separating the compressed gas from the liquid, means for conducting gas and liquid away from said separating means, a cooler having a cooling chamber provided with a vent, means for leading liquid to said cooler and back again to the rotor, and a float valve controlling said vent and operable when the liquid level in the cooling chamber drops below a predetermined point to provide for escape of trapped air from the cooling chamber.
17. In a compressor, a vertically disposed rotatable shaft, a fixed compressor part loosely surrounding said shaft and having a plurality of conduits therein, a rotor rotatable with the shaft above said fixed compressor part and having compression conduits communicable with the ends of the conduits of the fixed compressor part, means for delivering mixed gas and liquid into the inner end portions of each of said compression conduits, means for separating the compressed gas from the liquid, an annular chamber between the fixed compressor part and rotor into which

liquid from the rotor ducts flows by gravity when the compressor is idle, and means between said chamber and the rotor constructed to provide for the utilization of centrifugal force to automatically return the water from said chamber to the rotor ducts when the compressor is started.

18. In a compressor, a vertically disposed rotatable shaft, a fixed compressor part loosely surrounding said shaft and having a plurality of conduits therein, a rotor rotatable with the shaft above said fixed compressor part and having compression conduits communicable with the ends of the conduits of the fixed compressor part, means for delivering mixed gas and liquid into the inner end portions of each of said compression conduits, means for separating the compressed gas from the liquid, an annular chamber between the fixed compressor part and rotor into which liquid from the rotor ducts flows by gravity when the compressor is idle, means between said chamber

ber and the rotor constructed to provide for the utilization of centrifugal force to automatically return the water from said chamber to the rotor ducts when the compressor is started, and an annular ledge within said chamber for preventing said water in said chamber from traveling to the outer portion of the rotor.

19. In a compressor, a rotor having therein a plurality of compression conduits extending away from the rotor axis, means for delivering mixed gas and liquid into the inner portions of each of said conduits, means communicating with said compression conduits for separating the compressed gas from the liquid, means for conducting gas and liquid from said separating means, a source of cooling water, and means providing for the automatic admission of cooling water to the compressor only when the compressor is operating.

CARL A. BERGMANN. 20
